METALLIC RECEPTACLE

Edward D. Thompson, Warren, Ohio, assignor to
 The Stevens Metal Products Company, Niles,
 Ohio, a corporation of Ohio

Application September 5, 1933, Serial No. 688,107

2 Claims. (Cl. 220—10)

My invention relates to sheet metal receptacles such as drums, barrels and the like and relates more particularly to that class which is formed of relatively heavy gauge sheet, wherein either 5 or both of the end closures are double seamed to the body.

One of the objects of my invention resides in a method of forming a reinforced double seam between the walls of the body and the end closures. 10 Another object of the invention consists in reinforcing a double seamed end structure for metallic receptacles, whereby a very strong end structure is provided thus permitting rough treatment of the receptacles in transportation or 15 storing without danger of loosening or spreading the double seam.

A still further object of the invention consists in bonding the abutting walls of a metallic receptacle of the full or semi-insulated type circumferentially of the receptacle, before the end closure is double seamed to the end walls of the receptacle, whereby longitudinal movement between the respective walls of the body and/or the end closure is substantially eliminated, and 25 greater strength provided to resist buckling of the walls when the receptacle is dropped or is otherwise subjected to rough treatment.

Other objects and advantages of my invention will become more apparent as the following description of two embodiments thereof progresses, 30 reference being made to the accompanying drawing, in which like reference characters are employed to designate like parts throughout the same.

35 In the drawing:

Figure 1 is an elevation of a metallic receptacle embodying one form of my invention, the same being shown partly in section;

40 Figure 2 is a fragmentary section of the body walls of the receptacle, showing the same intimately bonded together circumferentially near their ends;

45 Figure 3 is a view similar to Figure 2 and illustrates the second step in carrying out this embodiment of my invention wherein the inner wall is flanged outwardly.

Figure 4 is a view of one of the end closures employed in the embodiment shown in Figure 1, 50 in which the walls of the end closure are intimately bonded together, the outer wall being flanged outwardly.

Figure 5 is a similar view showing the structures illustrated in Figures 3 and 4 assembled together. 55

Figure 6 is a view similar to that shown in Figure 5 in which the flanged walls of the body and end closure are rolled to form a double seam;

Figure 7 shows the application of a chime ring to the double seam and illustrates in full lines the completed seam; and,

Figure 8 illustrates a second embodiment of my invention which is particularly adapted for use in connection with receptacles of the semi-insulated type.

Referring first to Figures 1 to 7 inclusive, I will proceed to describe the double seam and method of forming the same according to the present invention with particular reference to the embodiment illustrated.

In containers of the full insulated type the side or body walls of the container usually comprise two shells fitted one within the other as at 1 and 2 respectively, the inner shell being of a uniform inside diameter until after it is inserted within the outer shell 1. The inner shell may then be bilged as indicated in the drawing. Referring particularly to Figure 2 it will be seen that when these shells are assembled the end of the inner shell projects beyond the end of the outer shell as indicated at 3. When the shells are so assembled they may be intimately bonded together circumferentially of the body as at 4, by any suitable means such as by welding. In this manner relative lengthwise movement of the shells 1 and 2 is prevented while and at the same time the end portions are materially strengthened at and in the vicinity of the weld. While perhaps a stronger bond may be obtained by a continuous circumferential weld, it is to be understood that the weld need not be continuous. The next step 30 consists in outwardly flanging the portion 3 of the inner shell as indicated in Figure 3.

Similarly, each end closure for the full insulated type may be formed by inserting the cup-shaped end piece 5 within the outer end closure 6. The abutting walls of the end closures 5 and 6 are similarly intimately bonded or welded as at 7, preferably circumferentially of the seam, there being an outwardly extending flange 8 formed on the outer end closure 6.

When the end walls of the body and the end closure are thus formed they are assembled as shown in Figure 5. In assembling these parts the end closure preferably fits snugly within the inner shell and is pressed downwardly in place as indicated in the figure, the flange 8 overlying the flange 3 as shown.

Further carrying out the process of double seaming the end structure and the flanges 3 and

8 are subjected to a rolling operation, so that the flange 8 is rolled inwardly and about the underside of the flange 3 as indicated in Figure 6.

The final step consists in applying the chime ring 9 which has a portion 10 which extends downwardly against the horizontal wall of the end closure 5 and is provided with a portion 11 which is bent downwardly as indicated by the arrow and dotted lines as shown in Figure 7 to the full line position in this figure, wherein the end 12 of the chime ring is bent inwardly toward the outer shell and upwardly against the roller flange 8. The chime ring is rolled into place in the usual manner.

15 It will be seen from the above that a double seam is formed which has an added advantage increased strength and reinforcing qualities in which, by intimately bonding the receptacle end closure walls and the body walls, preparatory to completion of the double seam, materially strengthens the formed end seam and the end structure of the receptacle when completed. This reinforcement is a further improvement because relative longitudinal movement of the receptacle body walls and end closure walls is eliminated. I have found where such relative movement is permitted the double seam is subject to spreading, this being particularly true where a filled receptacle is dropped but a few feet on its side bilged walls.

20 By my invention I believe that the bonding of the walls as described not only reinforces the end structure at and in the vicinity of these walls but helps to distribute the shocks to which the receptacle is subjected in rough handling.

25 In Figure 8 I have illustrated my invention as applied to a receptacle of the semi-insulated type. In this form of the invention the inner shell 2 is inserted in the outer shell 1 as previously described, the shells being intimately bonded together as at 4. In carrying out this form of my invention, however, the end closure 13 comprises a single cup-shaped member, the upstanding flange 14 being adapted to snugly fit against the upper end of the inner shell 2 when assembled 30 in place. The adjacent walls of the flange 14 and the shell 2 are also intimately bonded together as at 15, the bonds 4 and 15 preferably extending around the periphery of the container. After these walls are thus assembled and bonded together, the chime ring 16 may be applied in the usual manner and rolled so that the end 17 is tightly pressed against the outer shell wall 1.

35 It will be seen in connection with this embodiment of my invention that by intimately bonding the receptacle end walls I have accomplished the same advantages of reinforcement for the end structure as are accomplished in connection with the embodiment shown in Figures 1 to 7, likewise in the second embodiment relative longitudinal movement between the walls 1, 2 and 14 is prevented.

40 By my invention I have produced a metallic receptacle having fixed closed ends and which is extremely durable and rigid in use, thus permitting rough handling without danger of disturbing the same or causing leaks at the seam. Furthermore, the method of forming the end structure embodying my invention is extremely simple and inexpensive to carry out.

45 Various changes in the details of construction and arrangement of parts may be made without departing from the spirit of my invention or the scope of the appended claims.

50 I claim:

1. A metallic receptacle comprising inner and outer shells spaced apart except in the vicinity of their outer ends, the end portion of the inner shell overlapping the end of the outer shell, said ends of the shells being firmly bonded together, an end closure for the open end of said inner shell, said end closure comprising flanged members spaced apart throughout their body portion but closely fitting one within the other along their flanges, said closure flanges being firmly bonded together, the flange of the outermost member overlying the flange of the inner member and the overlapping end of the inner shell, said shell overlapping ends and closure overlying flange being subsequently rolled over the respective remaining shell and closure ends into a double seam.

2. A metallic receptacle comprising a body, an end closure for said body, said body comprising an inner shell and an outer shell spaced apart from the greater portion of their length and welded together circumferentially near their terminal ends, the end of said inner shell extending beyond said outer shell end, said end closure having a flange extending beyond said inner shell flange when the closure is in position to close the receptacle open end, said inner shell end and said cover flange being rolled outwardly over the peripheral edge of said outer shell end to form a double seam at the end of the receptacle.

EDWARD D. THOMPSON.
